ENGINE

James W. Kinnucan, Detroit, Mich.

Application April 27, 1933, Serial No. 668,153

6 Claims. (Cl. 123—81)

My invention relates to engines and more particularly to engines of the sleeve valve type, this invention pertaining more particularly to the construction of the sleeve valve means for controlling the valving functions of the engines. In engines of the sleeve valve type as aforesaid and in particular those engines having a flat head in which the re-entrant cylinder head portion is omitted, it has been found desirable to provide cylinder intake and exhaust ports spaced axially of the cylinder. Generally the pistons associated with engines of this type are arranged for cooperating operation with the sleeve valve means so as to partly control the engine cyclical events and in some instances it is found desirable to space the cylinder intake and exhaust ports a distance less than the stroke of said sleeve valve means in order to maintain the engine height within reasonable limits. Further, it is desirable to provide a plurality of such cylinder intake and exhaust ports in order to provide sufficient port area for the intake and exhaust of the engine gases. The foregoing factors were found to be controlling on the design of an engine of the aforesaid type, and because of the fact that the exhaust ports were preferably located on the same side of the engine as the intake ports, it was found that the particular port construction had a great deal to do with the engine design.

An object of my present invention is to construct an engine of the sleeve valve type in which the aforesaid difficulties are substantially eliminated.

Another object of my invention is to provide an improved porting arrangement and associated sleeve valve means for controlling said ports in engines of the aforesaid type, whereby to provide an engine having an improved operating performance and an increased power output, but of minimum size and weight.

A further object of my present invention is to construct an engine of the aforesaid type provided with sleeve valve means so constructed and arranged as to permit a relatively longitudinal spacing of the cylinder intake and exhaust ports of the type specified in which the sleeve ports controlling one of the cylinder ports is caused to travel in a path extending in the region intermediate other cylinder ports.

For a more detailed understanding of my invention, reference may be had to the accompanying drawings which illustrate one form which my invention may assume, and in which:

Fig. 1 is a vertical transverse sectional view of a typical engine cylinder constructed in accordance with my invention.

Fig. 2 is a port diagram showing the relationship between cylinder and sleeve intake and exhaust ports, said ports being respectively positioned at the beginning of the power stroke,

Fig. 3 is a port diagram showing the said ports at the time when the lower exhaust opens,

Fig. 4 is a port diagram showing the position of the ports when the upper exhaust opens,

Fig. 5 is a port diagram showing the position of said ports when the lower exhaust opens,

Fig. 6 is a port diagram showing the relationship between said ports when the intake opens,

Fig. 7 is a port diagram showing the upper exhaust closing,

Fig. 8 is a port diagram showing the intake closing, and

Fig. 9 is a timing diagram illustrating the angular position of the crankshaft for the various critical positions of the sleeve valve means.

In the accompanying drawings I have illustrated an engine A which in general includes a cylinder block 10 having a cylinder 11, closed at its outer ends by a cylinder head B which is adapted to be secured to the cylinder block by bolts 12 or other suitable fastening devices. Sleeve valve means 13 are associated with the engine cylinder 11 and are driven from the engine crankshaft 14 by any suitable driving mechanism. In the illustrated embodiment of my invention as shown in the drawings, I have provided a sleeve valve of the combined movement type, said sleeve having a combined oscillating and reciprocating motion with respect to the cylinder and sleeve axes whereby any point on the sleeve traverses a closed path in performing its valving functions, said sleeve valve being preferably driven from the wobble shaft 15 by means of the wobble yoke or link 16 connected with the sleeve by means of the ball and socket connection 17, this wobble shaft being driven from the crankshaft by means of a chain or other suitable driving mechanism.

The engine herein illustrated is commonly referred to as an engine of the flat-head type; that is, the cylinder head is not provided with a re-entrant head portion depending within the cylinder and the sleeve valve means 13 is so arranged as to have the upper portion of said sleeve exposed to the combustion chamber C. The head carries the usual spark plug or other suitable ignition device having spark terminals 16' extended into the combustion chamber C.

A piston 17 is operable in the cylinder and is connected to the crank 18 of the crankshaft 14 by means of a suitable connecting rod 19.

The engine cylinder is provided with intake ports 20, and upper and lower exhaust ports 21 and 22 respectively, and it will be noted that the exhaust port 22 is spaced axially inwardly of the cylinder from the intake port 20 and is preferably located on the same side of the engine.

10 I preferably provide a plurality of such intake ports 20 which are spaced angularly around the engine cylinder, and also a plurality of such exhaust ports 22 which are in turn spaced angularly around the cylinder. The sleeve 13 is provided with intake and exhaust ports 23 and 24 respectively, some of which are adapted to cooperate with the cylinder intake and exhaust ports 20 and 22 respectively for controlling the valving functions of the engine.

20 My invention is particularly concerned with cylinder ports 20, 22 and the cooperating sleeve ports 23, 24. In the port diagrams shown in Figs. 2 to 8 inclusive, I have shown a curve 25 which graphically illustrates the path taken by any point 26 on the sleeve during one cycle of the sleeve movement. It will be noted that the major axis 27 of the elliptical curve 25 is greater than the distance 28 between the intake and exhaust ports 20 and 22 of the cylinder. In Fig. 2, I have illustrated a number of positions of the sleeve exhaust port 22 as the same is moved into the region intermediate two of the cylinder intake ports 20. Position I shows this exhaust port leaving the aforesaid region, position designated by II shows this port entering said region, while position designated by III shows the port 24 near its outermost position of travel. In the claims I have described this action by specifying a sleeve exhaust port which is arranged to traverse a path extending into the region intermediate a pair of adjacent cylinder intake ports. It will be also noted that the path taken by the sleeve exhaust ports is such that only a portion of said path extends into this region intermediate adjacent cylinder intake ports. It will be also noted that the distance 29 between adjacent cylinder intake ports is less than the sum of the distances 30 and 31 respectively measuring the width of the exhaust port 24 and the total oscillating movement of said ports as claimed by the curve 25.

55 It will further be noted on observing Figs. 2 to 8 inclusive that the piston substantially masks said sleeve exhaust port when the same is travelling in that region lying intermediate the cylinder intake ports as said piston is travelling substantially in the vicinity of its outermost position of travel. The piston outer edge being shown in these figures by dotted lines, together with arrows indicating the motion of the piston. 60 The arrangement as described in the foregoing paragraphs provides a construction which permits the cylinder intake and exhaust ports 20 and 22 to be relatively closely spaced axially of the engine cylinder.

65 In its broadest aspects the principles of my invention may be incorporated in engines other than those of the type employing a sleeve valve of the combined movement type as herein illustrated. Therefore, I do not limit my invention to the specific type of sleeve valve means as shown, since beneficial results may be obtained by employing this invention with other types of engines.

70 Although I have illustrated but one form of

my invention and have described in detail but a single application thereof, it will be apparent to those skilled in the art to which my invention pertains that various modifications and changes may be made therein without departing from the spirit of my invention or from the scope of the appended claims.

What I claim as my invention is:

1. In a sleeve valve engine having a cylinder ported for intake and exhaust, sleeve valve means of the combined movement type having intake and exhaust ports respectively cooperating with the cylinder intake and exhaust ports whereby to control the engine cyclical events, said sleeve exhaust port being arranged to traverse a path extending into the region intermediate a pair of adjacent cylinder intake ports. 80

2. In a sleeve valve engine having a cylinder provided with intake and exhaust ports spaced axially of the cylinder, sleeve valve means of the combined movement type having intake and exhaust ports respectively cooperating with the cylinder intake and exhaust ports whereby to control the engine cyclical events, said sleeve exhaust port being arranged to traverse a path 95 extending into the region intermediate a pair of adjacent cylinder intake ports. 100

3. A sleeve valve engine having a cylinder ported for intake and exhaust, sleeve valve means having a movement axially of the cylinder and provided with intake and exhaust ports respectively cooperating with the cylinder intake and exhaust ports to control the engine cyclical events, said cylinder intake and exhaust ports being spaced axially of the cylinder an amount 105 less than the stroke of the sleeve, one of said sleeve ports being arranged to traverse a path extending into the region intermediate a pair of adjacent cylinder ports cooperating with said other sleeve port. 110

4. A sleeve valve engine having a cylinder ported for intake and exhaust, sleeve valve means having a movement axially of the cylinder and provided with intake and exhaust ports respectively cooperating with the cylinder intake and exhaust ports to control the engine cyclical events, said cylinder exhaust port being spaced from said intake ports axially and inwardly of the cylinder an amount less than the stroke of the sleeve, said sleeve exhaust port being arranged to traverse a path extending into the region intermediate a pair of adjacent cylinder intake ports. 115

5. A sleeve valve engine having a cylinder ported for intake and exhaust, a single sleeve valve means of the combined movement type in which any point on the sleeve traverses an elliptical path with respect to the cylinder and sleeve axes and having intake and exhaust ports cooperating with the cylinder intake and exhaust ports to control the engine cyclical events, said cylinder having a plurality of intake ports angularly spaced apart an amount less than the sum of the oscillating motion of the sleeve and the width of the sleeve exhaust 130 port, said cylinder exhaust port spaced axially inwardly of the cylinder from the cylinder intake ports, said sleeve exhaust port being arranged to traverse a path extending into the region intermediate a pair of adjacent cylinder 135 intake ports. 140

6. In a sleeve valve engine having a cylinder ported for intake and exhaust, sleeve valve means of the combined movement type having intake and exhaust ports respectively controlling 150

the cylinder intake and exhaust ports, a piston operable in said cylinder and cooperating with said sleeve valve means for controlling in part the engine cyclical events, said sleeve exhaust port being arranged to traverse a path extending into the region intermediate a pair of adjacent cylinder intake ports, said piston operating in the vicinity of its outermost position of travel during the time said sleeve exhaust port is traversing the region intermediate said cylinder intake ports, whereby to substantially mask said sleeve exhaust port when same is travelling in the vicinity of said cylinder intake ports. 80
